UNITED STATES PATENT OFFICE.

WILLIAM SPALCKHAVER, OF NEW YORK, N. Y., ASSIGNOR TO ROBERT HOE,
OF NEW YORK, N. Y.

CYLINDER-MACHINE FOR PRINTING ON SHEETS.

SPECIFICATION forming part of Letters Patent No. 703,491, dated July 1, 1902.

Application filed April 12, 1901. Serial No. 55,581. (No model.)

To all whom it may concern:

Be it known that I, WILLIAM SPALCKHAVER, a citizen of the United States, residing at New York, county of Kings, and State of New York, 5 have invented certain new and useful Improvements in Cylinder-Machines for Printing on Sheets, fully described and represented in the following specification and the accompanying drawings, forming a part of the 10 same.

This invention relates to certain improvements in printing-machines.

In cylinder printing-machines for printing on sheets as ordinarily constructed the sheet-presenting means—such, for instance, as the feed-board—is ordinarily arranged to present the sheets to the sheet-taking devices of the cylinder at a point above the axial center of the cylinder. Machines have, however, been 20 constructed in which the feed-board was arranged to present sheets to the cylinder at a point below the axial center thereof. While machines arranged in this way have certain advantages over machines in which the feed-board is arranged above the axial center, they are objectionable for the reason that the shadow cast on the feed-board by the cylinder prevents the feeder from accurately positioning the sheets. Furthermore, in the construction 25 in which it has been proposed to use a feed-board which delivers the sheets below the axial center of the cylinder the devices for positioning the sheets—such, for instance, as a front-stop mechanism—have been 30 crude and unsatisfactory.

One of the objects of this invention is to produce an improved cylinder sheet-printing machine of the type in which the sheets are presented to the cylinder below the axial center thereof, the construction of the machine being such that the feeder can see to feed the sheets.

A further object of the invention is to improve the sheet-positioning devices of the 40 class of machines referred to.

With these and other objects in view the invention consists in certain constructions and in certain parts, improvements, and combinations, as will be hereinafter fully 45 described, and then specifically pointed out in the claims hereunto appended.

In the accompanying drawings, in which like characters of reference indicate the same parts, Figure 1 is a side elevation, partly in section, of so much of a printing-machine as 55 is necessary to an understanding of the invention. Fig. 2 is a plan view of the construction shown in Fig. 1.

Referring to the drawings, which illustrate one embodiment of the invention, 1 indicates 60 a frame, which may be of any usual form or construction. The sheet-carrying member of the printing-couple is mounted in this frame and is indicated at 2, said member being a cylinder which is mounted on a shaft 3, supported in suitable boxes in the frame. In 65 the construction illustrated the sheet-carrying member is an impression-cylinder and is therefore provided with an impression-surface 4. Any suitable form of printing member or members may be used in connection with the impression-cylinder to produce a 70 printing-couple.

The form of machine which has been selected to illustrate the invention is a multi-color machine, and two coöperating form-carrying members are therefore shown, said members consisting of form-cylinders 5 and 6, said cylinders being mounted on shafts 7 75 and 8. The shafts 7 and 8 may be supported in 80 the frame in any suitable manner. As shown, they are mounted in eccentric bearings 9 and 10, so that the form-carrying cylinders may be readily moved away from the impression-cylinder for the purpose of inking up or for 85 other reasons. In the construction shown the eccentric bearings are connected by means of a rod 11, and the bearing 9 has secured to it an arm 12, which carries a segment 13. This segment coöperates with 90 another segment 14, which is pivoted at 15 to the frame of the machine. This segment 14 is operated by means of a hand-lever 16 or in any other suitable manner.

The form-cylinders in the present machine 95 are designed to carry aluminium plates, although any suitable printing-surfaces may be used therefor. A suitable inking apparatus 17 and damping apparatus 18 will be provided for each form-carrying cylinder. 100

While the construction so far described is a convenient one for illustrating the inven-

tion, it is to be understood that the invention is in no way dependent upon this construction and that any other form of printing couple or couples may be employed.

5 The means for presenting the sheet to be printed to the cylinder below its axial center may be varied within wide limits. In the present construction the presenting means comprise a feed-board 19. While this feed-board may be variously arranged and located, it will preferably be so located as to present the sheet to the cylinder beneath the cylinder, as shown. When, as is usual in this type of machines, the cylinder is constructed 15 with a continuous surface, the feeder has difficulty, because of the shadow thrown by the cylinder on the feed-board, in properly positioning the sheet on the board so that it can be taken by the sheet-taking devices of 20 the cylinder, which in the present instance are shown as consisting of ordinary grippers 20. The cylinder is therefore cut away opposite the impression-surface, so that after 25 the impression-surface has passed the feed-board the light can have access to the end of the board, and the feeder can thus see to properly position his sheet. In order to run a cylinder at high rates of speed, however, it is desirable that the cylinder be balanced—that 30 is, that the weight of the cylinder be substantially equally disposed around its center. In the present construction, therefore, the cylinder will be provided with a counterweighting-segment 21, said segment being arranged 35 nearer the axis of the cylinder than the sheet-carrying or impression surface 4. By thus arranging the counterweighting-segment within the periphery of the cylinder or near its axis a cylinder is produced which will run 40 evenly at high speed and which will not cast a shadow upon the feed-board so as to interfere with the proper placing of the sheet.

A suitable front stop will be provided, as is usual, to assist the feeder in properly positioning his sheet. Front stops as ordinarily 45 constructed are arranged above the feed-board and move upward away from the board. In a construction, however, where the board is arranged to present its sheet below the 50 cylinder it will be seen that there is no room to arrange the front stop in the ordinary manner, so that it can move up above the board at the time when the sheet is to be taken. In the present construction, therefore, 55 the front stop is arranged so as to move below the board at the time when the sheet is taken. Any suitable form of front-stop mechanism may be employed. In the construction shown the front stop consists of the 60 usual fingers 22, said fingers being mounted on a rock-shaft 23, which is located below the plane of the board.

Any suitable mechanism may be employed 65 for the purpose of rocking the shaft to move the front-stop fingers out of the way when the sheet is to be taken. In the present construction the shaft 23 is provided with an

arm 24, which is connected by means of a link 25 to one of the arms 26 of a bell-crank lever 26 27, which is pivoted at 28 to the 70 frame of the machine. The cylinder is provided with a cam 29, which serves to operate the arm 27 of the bell-crank at suitable times, said arm being provided with a suitable bowl or roller.

The sheet-delivery means employed may be of any suitable description; but when the sheet is to be delivered with the last-printed side out such delivery means will preferably be arranged over the feed-board. In the 80 present construction the delivery means consists of suitable tapes 30, which run over pulleys 31 32, mounted on suitable shafts. A suitable switch or bridge, consisting of fingers 33, rests upon the periphery of the cylinder, as usual, in order to guide the sheets away from the cylinder, and a suitable nipping-roll 34 may be employed, if desired, to coöperate with the tapes 30. The delivery mechanism described is of a usual form and 85 any other form may be substituted for it, if desired.

The gearing by which the cylinder is driven may be of any usual or desired description. In the construction shown the power-shaft 95 35, which carries the driving-pulley 36, is provided with a driving-pinion 37, which meshes with a gear 38, mounted on the cylinder-shaft 3. The shafts of the form-cylinders are provided with gears 39 40, which mesh 100 with the gear 38.

The operation of the construction will be clear from the description before given. It will be noted, however, that a machine constructed as described has certain marked advantages. The feed-board can be brought close to the floor of the room in which the machine is located, so that sheets can be easily supplied to the feeder, and, furthermore, the sheets can be printed and delivered 110 105 printed side up on a single revolution of the cylinder, so that the product of the machine can be largely increased.

While the construction shown for carrying the invention into effect is a preferred embodiment of the same, it will be understood that the invention is not to be limited to the specific details of construction shown and described, but that many changes may be made therein without departing from the invention. 120 115 125

What is claimed is—

1. In a printing-machine, the combination with the rotating sheet-carrying cylinder of a printing-couple, said cylinder being cut away opposite the sheet-supporting surface, 125 of a feed-board arranged to present a sheet beneath the cylinder, substantially as described.

2. In a printing-machine, the combination with the rotating sheet-carrying cylinder of a printing-couple, said cylinder being cut away opposite the sheet-supporting surface, of a feed-board arranged to present a sheet beneath the cylinder, and a delivery mechan- 130

- ism arranged over the feed-board, substantially as described.
3. In a printing-machine, the combination with the rotating sheet-carrying cylinder of a printing-couple, said cylinder being cut away opposite the sheet-supporting surface and having a counterweighting-segment which is nearer the center of the cylinder than the sheet-supporting surface, of a feed-board arranged to present a sheet beneath the cylinder, substantially as described.
4. In a printing-machine, the combination with the rotating sheet-carrying cylinder of a printing-couple, said cylinder being cut away opposite the sheet-supporting surface and having a counterweighting-segment which is nearer the center of the cylinder than the sheet-supporting surface, of a feed-board arranged to present a sheet beneath the cylinder, and a delivery mechanism arranged over the feed-board, substantially as described.
5. In a printing-machine, the combination with the rotating sheet-carrying cylinder of a printing-couple, said cylinder being cut away opposite the sheet-supporting surface, of a feed-board, a front stop coöperating with the feed-board, means for moving the front stop below the plane of the board, and a delivery mechanism arranged over the feed-board, substantially as described.
6. In a printing-machine, the combination with the rotating sheet-carrying cylinder of a printing-couple, said cylinder being cut away opposite the sheet-supporting surface and having a counterweighting-segment arranged nearer the center of the cylinder than the sheet-supporting surface, of a feed-board arranged to present a sheet beneath the cylinder, a front stop coöperating with the board, and means for moving the stop below the plane of the board, substantially as described.
7. In a printing-machine, the combination with the rotating sheet-carrying cylinder of a printing-couple, said cylinder being cut away opposite the sheet-supporting surface and having a counterweighting-segment arranged nearer the center of the cylinder than the sheet-supporting surface, of a feed-board arranged to present a sheet beneath the cylinder, a front stop coöperating with the board, means for moving the stop below the plane of the board, and a delivery mechanism arranged over the feed-board, substantially as described.
8. In a printing-machine, the combination with the rotating sheet-carrying cylinder of a printing-couple, said cylinder being cut away opposite the sheet-supporting surface, of a feed-board arranged to present a sheet beneath the cylinder, a front stop, a rock-shaft on which the stop is mounted located beneath the feed-board, and means for rocking the
- shaft to throw the stop below the feed-board, substantially as described.
9. In a printing-machine, the combination with the rotating sheet-carrying cylinder of a printing-couple, said cylinder being cut away opposite the sheet-supporting surface and having a counterweighting-segment arranged nearer the center of the cylinder than the sheet-supporting surface, of a feed-board arranged to present a sheet beneath the cylinder, a front stop, a rock-shaft on which the stop is mounted located beneath the feed-board, and means for rocking the shaft to throw the stop below the feed-board, substantially as described.
10. In a printing-machine, the combination with the rotating sheet-carrying cylinder of a printing-couple, said cylinder being cut away opposite the sheet-supporting surface and having a counterweighting-segment arranged nearer the center of the cylinder than the sheet-supporting surface, of a feed-board arranged to present a sheet beneath the cylinder, a front stop, a rock-shaft on which the stop is mounted located beneath the feed-board, means for rocking the shaft to throw the stop below the feed-board, and a delivery mechanism arranged over the feed-board, substantially as described.
11. In a printing-machine, the combination with a rotating impression-cylinder, said cylinder being cut away on the side opposite the impression-surface, a counterweighting-segment arranged nearer the center of the cylinder than the impression-surface, of a feed-board arranged to present a sheet beneath the cylinder, a rock-shaft mounted below the board, a front stop on the rock-shaft, a cam on the cylinder, and means whereby said cam rocks the shaft to throw the front stop below the board, substantially as described.
12. In a printing-machine, the combination with a rotating impression-cylinder, said cylinder being cut away on the side opposite the impression-surface, a counterweighting-segment arranged nearer the center of the cylinder than the impression-surface, of a feed-board arranged to present a sheet beneath the cylinder, a rock-shaft mounted below the board, a front stop on the rock-shaft, a cam on the cylinder, means whereby said cam rocks the shaft to throw the front stop below the board, and a delivery mechanism arranged over the feed-board, substantially as described.

In testimony whereof I have hereunto set my hand in the presence of two subscribing witnesses.
